(57) CLAIM

I claim the ornamental design for covered container with images, as shown and described.

DESCRIPTION

FIG. 1 is an exploded perspective view of covered container with image showing my new design;

FIG. 2 is an exploded front elevational view thereof;

FIG. 3 is an exploded rear elevational view thereof;

FIG. 4 is an exploded left side elevational view thereof;

FIG. 5 is a front elevational view thereof; shown in closed position;

FIG. 6 is a top plan view of the lid thereof;

FIG. 7 is a bottom plan view of the lid thereof;

FIG. 8 is a top plan view of the inside base of the container thereof; and,

FIG. 9 is a bottom plan view of the base of the container.
